UNITED STATES PATENT OFFICE.

WILLIAM R. PAYNE AND WILLIAM T. DRUMMOND, OF SCARBRO, WEST VIRGINIA.

RAILWAY STAY-ROD.

1,111,612.

Specification of Letters Patent. Patented Sept. 22, 1914.

Application filed April 13, 1914. Serial No. 831,524.

To all whom it may concern:

Be it known that we, WILLIAM R. PAYNE and WILLIAM T. DRUMMOND, citizens of the United States, residing at Scarbro, in the county of Fayette and State of West Virginia, have invented certain new and useful Improvements in Railway Stay-Rods; and we do declare the following to be a full, clear, and exact description of the invention, such as will enable others skilled in the art to which it appertains to make and use the same.

This invention relates to new and useful improvements in track construction and more particularly to means for preventing the spreading of rails and our object is to provide an improved tie or stay rod construction which will positively secure a pair of rails in position with respect to one another.

A further object of the invention resides in providing such a construction as may eliminate the use of ties for supporting rails.

A still further object resides in providing thimble-like clamping members for engagement with the stay rod and base flanges of the rails for positively securing the latter in spaced relation with respect to one another.

A still further object resides in providing a device which is simple and durable in construction, inexpensive to manufacture, and one that will be very efficient in use.

With these and other objects in view our invention consists in the novel features of construction, combination and arrangement of parts as will be hereinafter referred to and more particularly pointed out in the specification and claims.

In the accompanying drawings forming a part of this application:—Fig. 1 is a side elevation of a device constructed in accordance with our invention and applied to use the rails being shown in section. Fig. 2 is a vertical section therethrough. Fig. 3 is a transverse section as seen on line 3—3 of Fig. 2. Fig. 4 is a similar view as seen on line 4—4 of Fig. 2. Fig. 5 is a perspective view of one of the clamping members used on the device. Fig. 6 is a similar view of another clamping member of the device. Fig. 7 is a vertical section through the device supplied with non-conducting members, when the rails are electrically energized.

In describing the invention we shall refer to the drawings in which similar reference characters designate corresponding parts throughout the several views and in which 1 and 2 indicate respectively a pair of rail sections which are adapted to be secured in position with respect to one another through the medium of my improved stay rod construction. The referred to construction comprises a rod 3 which is threaded for a considerable portion of its length continuing from one end thereof as indicated at 4. The opposite end of this rod 3 is also threaded for a shorter distance than indicated at 4 and the latter threaded portion is indicated as 5. Continuing from the last mentioned threaded portion 5 is a portion which is designed square in cross section the same being indicated at 6. This squared portion 6 provides a shoulder 7 on the rod 3, the purpose of which will be hereinafter and more particularly set forth. For the sake of convenience, the end of the rod 3 having the threaded portion 5 and the square portion 6 thereon will be termed the stationary end of the rod inasmuch as the opposite end of the same forms a means for application of the adjustable mechanism for the device. For use in connection with the stationary end of the rod 3, are provided the clamping members 8 and 9 said clamping members being of thimble or sleeve-like formation for ready application to the rod. The member 8 has the bore thereof designed square in cross section so as to be readily received on the squared portion 6 of the rod 3 and when this member 8 is applied on the rod, the one end thereof abuts the shoulder 7. Each of the members 8 and 9 has a V-shaped slot formed therein which affords a space for the reception of a base flange of the rail therein. It will be appreciated that when the member 8 is first applied to the rod 3 that the base flange of the one rail 2 may be received in the slotted portion 10 thereof whereupon the additional clamping member 9 may be applied to the rod 3 so as to receive in its slotted portion 10 the other base flange of the rail. When these members 8 and 9 are so applied, a clamping nut 11 is applied on the threaded end 5 of said rod 3, whereby to positively secure said clamping members in position and also secure the rail with respect to the rod. This, as stated above, forms

the stationary portion of the device. In order to prevent any possible movement of said members 8 and 9 with respect to the rail 2, the member 8 is provided with an additional V-shaped slotted portion indicated as 12. In this manner a pair of biting teeth are provided on said member for engagement with the web of the rail and thus a more secure engagement may be had between said member and said rail. Of course if desired, means may also be provided in connection with the web of the rail for engagement with the space between the biting teeth thus making the engagement still more secure.

The adjustable sections of the device for use in connection with the rail 1 consist of a pair of clamping members 13 and 14 which are designed identical to that indicated as 9, the same being provided with the V-shaped slots for engagement with the base flanges of said rail. A nut 15 is applied on the threaded portion 4 of said rod 3 prior to the application of the clamping member 14 thereon and an additional nut 16 is provided for application thereto after the clamping members have been properly positioned with respect to said rail and thus it will be seen that said clamping members 30 may be positively secured in engagement with the tie rod and with said rail. It will be seen further, however, that by a mere adjustment of said nuts 15 and 16 said rail 1 may be readily adjusted laterally on the rod 3 to be adjusted with respect to the other rail 2 which, as stated above, is said to be stationarily secured in position.

In operation, assuming that the rails 1 and 2 are properly positioned on the ground, 40 the tie rod 3 is positioned thereunder and the member 8 first applied to the end which, as indicated above, is the stationary end of the device. The rail 2 is then applied to permit the one base flange thereof to be received in the slotted portion 10 of said member 8, whereupon said member 9 is applied to the tie rod so as to receive in its slotted portion 10 the other base flange of said rail. The nut 11 is then properly applied to the 50 threaded portion 5, it being understood, of course that a washer is applied to the rod 5 with the application of this nut. Having thus properly secured the one rail 2 in position on the rod 3 the nut 15 is then properly applied to the threaded portion 4 of said rod 3. The member 14 is then applied to the rod 3 to abut said nut 15 whereupon the rail 1 is positioned to permit its one base flange to be received in the slotted V-shaped 55 portion 10 of said member 14. The member 13 is then applied to engage the other base flange of the rail, whereupon the outer nut 16 is secured in place. By a mere adjustment of the nut 15 it will be seen that a 60 proper position of the rail 1 may be ob-

tained, and when properly positioned with respect to said rail 2 said nuts 15 and 16 are turned home against the ends of said members 14 and 13, respectively, which will positively secure said rail in its adjusted and desired position. As indicated above, washers are of course applied on the bolt or rod 3 prior to the application of the nuts in position. When this particular method of securing the rails in position, so as to prevent spreading thereof, is used in connection with a signaling system wherein a circuit is passed through portions of the rails, it is necessary, of course, to insulate portions of the device to prevent short circuiting. 75 This is true in view of the tie rod connection as shown at 3 and we accomplish this result of insulating the parts by the provision of sleeve members 17 which are formed of fiber or other non-conducting material. 80 These sleeves are applied to the rod 3 prior to the application of the members 8, 9, 13, and 14 thereto and the washers used in connection with the device are also formed of fiber or other non-conducting material, so 85 the clamping members and the nuts will be entirely insulated from the rod 3 which forms the connection between the parts of the device. Thus it will be seen that we have provided a structure which will positively 90 prevent rails from spreading and which will eliminate the use of ties for said rails. It will also be seen that the structure for accomplishing this result is simple and durable in construction and inexpensive to 95 manufacture.

While we have described the preferred embodiment of the invention it will be understood that the same is capable of various modifications, within the scope of the appended claims.

Having thus described our invention, what we claim is:

1. In a device of the class described, the combination with a pair of rail sections; of a tie rod, sleeve-like clamping members applied thereto in pairs and the clamping members of each pair having their inner opposed ends slotted to receive the base flanges of said rails therein, means permanently formed adjacent one end of said rod to provide a stop for one pair of clamping members and to stationarily secure one rail on the rod and means in connection with the other pair of clamping members for adjustably securing the other rail on said rod. 110

2. In a device of the class described, the combination with a pair of rail sections; of a tie rod having a shoulder formed adjacent one end thereof the last mentioned end of said rod being threaded, a pair of clamping members of sleeve-like design applied to the last mentioned end of said tie rod, the one clamping member abutting said shoulder and both of said clamping members having 115 120 125 130

their inner opposed ends slotted to receive the base flanges of the one rail therein, means in engagement with the threaded end of said tie rod to positively secure the 5 clamping members in position on the base flanges of the rails whereby to secure the latter on the tie rod, and means in connection with the other end of said tie rod and the other rail to adjustably secure the latter 10 on said rod.

3. In a device of the class described, the combination with a rail; of a tie rod having a shoulder formed thereon adjacent one end of the same, the last mentioned end of said 15 rod being also threaded, a pair of sleeve-like clamping members applied to the last mentioned end of said rod to permit one of said members to abut the shoulder thereon, the inner opposed ends of said clamping members being provided with V-shaped slots to receive the base flanges of said rails therein, means to prevent the rotation of the innermost clamping member on said tie rod, a nut applied to the threaded end of said 20 tie rod for engagement with the outer of said clamping members whereby to positively secure the latter in engagement with said rail and tie rod, and means for adjustably securing another rail to the opposite 25 end of said tie rod.

4. In a device of the class described, the combination with a rail, of a tie rod provided with a shoulder at a point adjacent one end thereof, said tie rod being threaded at the last mentioned end, that portion of 35 said tie rod between the shoulder and the threaded portion thereof being designed square in cross section, a sleeve-like member applied to the end of said tie rod, the bore thereof being square in cross section to be 40 received on the squared portion of said tie rod, an additional sleeve-like member applied on said last mentioned end of the tie rod, the inner opposed ends of said sleeve-like member being provided with V-shaped 45 slots for the reception of the base flanges of said rails, a nut applied to the outer threaded end of said tie rod to secure said sleeve-like clamping members on said rod and rail to positively secure the latter on the former, 50 and means for adjustably securing another rail on the opposite end of said tie rod.

In testimony whereof we have hereunto set our hands in presence of two subscribing witnesses.

WILLIAM R. PAYNE.

WILLIAM T. DRUMMOND.
